CLAIM

The ornamental design for a holder for optical discs, as shown and described.

DESCRIPTION

FIG. 1 is a perspective view principally illustrating the front, top and right side of the holder for optical discs.

FIG. 2 is a front view of the holder for optical discs.

FIG. 3 is a top view of the holder for optical discs, the bottom view being a mirror image thereof.

FIG. 4 is a side view of the right side of the holder for optical discs.

FIG. 5 is a side view of the left side of the holder for optical discs.

FIG. 6 is a front perspective view of the holder for optical discs with the two portions moved apart; and,

FIG. 7 is a back perspective view of the holder for optical discs with the two portions moved apart.
